VIBRATORY CONVEYER OR MOTOR AND
MEANS FOR CONTROLLING SAMELee P. Doyle, Columbus, Ohio, assignor to The
Traylor Vibrator Company, a corporation of
Colorado

Application November 5, 1938, Serial No. 239,088

7 Claims. (Cl. 172—240)

This invention relates to an electrical system including a vibratory conveyer having a vibratory electro-magnetic motor and means for controlling the same to maintain a substantially constant feed rate of the conveyer or a constant amplitude of vibration of the motor.

An object of the invention is to provide an improved apparatus for conveying material at a substantially constant rate.

Another object of the invention is to provide an improved control system for maintaining at a substantially constant value the amplitude of vibration of a vibratory electro-magnetic motor.

Other objects of the invention will appear hereinafter, the novel features and combinations being set forth in the appended claims.

In the accompanying drawings,

Fig. 1 is a side elevational view of a vibratory conveyer or feeder which forms a portion of my invention showing also a part of the control mechanism for maintaining its feed rate substantially constant.

Fig. 2 is a perspective view of a portion of the electrical pick-up mechanism employed in carrying out my invention;

Fig. 3 is a front elevational view of another portion of the electrical pick-up mechanism with the cover plate removed;

Fig. 4 is a sectional elevational view of the mechanism of Fig. 3; and

Fig. 5 is a wiring diagram of the control system.

Referring particularly to Fig. 1 of the drawings, there is seen a vibratory conveyer or feeder 10 of the electro-magnetic type which, in general, follows the structure disclosed in the application of James A. Flint, Serial No. 73,318, filed April 8, 1936, now Patent No. 2,251,586, dated August 5, 1941, entitled Vibratory feeder and screen.

Briefly described, said conveyer or feeder 10 includes a deck 11 which has a material supporting bottom and which is supported in part from a superstructure 12 by a flexible cable and spring means 13. Rigidly attached to said deck 11 as by bolts 14 is an armature shaft 15 through which thread a plurality of stacked spring bars 16 clamped at their centers to said armature shaft 15 and at their opposite ends to a main frame casting 17, which main frame casting is supported by legs 18 resting upon coil spring supports 19. The lower end of the armature shaft 15 is connected by a bracket 20 to an armature 21 of laminated steel. Spaced from the armature 21 is a field structure 22 including a

U-shaped laminated core 23 and a field winding 24 adjustably supported by brackets 25 from U-shaped supports 26 by way of adjusting screws 27, the U-shaped supports 26 being attached to the main frame casting 17.

The members above described, except for the deck 11, constitute a vibratory electro-magnetic motor designated generally by the reference character 28. To balance the deck 11 to prevent undue twisting of the spring bars 16 the lower end of the armature shaft 15 is connected to the rear end of the deck by an upstanding bracket 29.

The amplitude of vibration of the deck 11 is determined in part by the current flow in the field winding 24 and in part by the load on said deck 11. It is extremely desirable in many instances to maintain the amplitude of vibration and thus the feed rate of the conveyer or feeder substantially constant, assuming the depth of the material in the feeder to be substantially constant. This last mentioned condition can be realized by providing a gate in the bottom of a feed hopper which feeds the conveyer 10.

Another condition which is often encountered is that a constant amplitude of vibration is desired without regard to the feed rate being constant, and it is desirable to maintain this constant amplitude at a relatively low value. For example, when material is to be fed to a cooler in a relatively uniform and relatively thin bed, the amplitude of vibration of the conveyer or feeder 10 is preferably relatively low. If this amplitude is set at a low value for a relatively small amount of material on the deck 11 the vibration of said deck 11 will substantially cease in case a very heavy load is discharged thereon without an increase in current to the motor 28. The method and system herein disclosed is operated automatically to maintain this low rate feeding of material by spreading it out in a thin bed, even though the material may be fed to the deck 11 in batches of appreciable weight.

To maintain at a substantially constant value the amplitude of vibration of the deck 11 and of the vibratory motor 28, I provide an automatic control system now to be described. Associated with the conveyer or feeder 10 or with the motor 28 is an electrical pick-up mechanism which is preferably of a form adapted to generate a potential which is proportional to the amplitude of vibration of the deck 11 or armature shaft 15. In the drawings I have illustrated one form of such electrical pick-up mechanism which comprises a vibratory member 30 shown in detail in

Fig. 2 of the drawings. Said vibratory member 30 comprises a base 31 having therein a hole 32 through which a machine screw 33 (see Fig. 1) is adapted to pass and anchor the vibratory member 30 to the deck 11, or any portion of the vibratory motor 28 which is rigidly attached to the armature shaft 15.

At one end the base 31 is provided with an up-standing plate 34 to which is clamped a steel vibratory reed 35 by means of a clamping bar 36. The free end of the reed 35 carries a steel block 37. Intermediate its ends the reed 35 may be adjustably clamped by clamp screws 38 carried upon a bifurcated bracket 39 supported by the base 31.

Cooperating with the vibratory mechanism 30 is a stationary mechanism 40 illustrated in detail in Figs. 3 and 4 of the drawings which is supported by the supports 26, or any other portion of the motor 28 which is rigidly attached to the main frame 17. The stationary mechanism 40 is essentially an ordinary telephone receiver comprising a permanent magnet 41, the legs of which are provided with coils 42 which are supported upon a base 43 and contained within a housing 44 having a removable cap 45 provided with a central opening to expose the ends of the magnet 41. The housing 44 is rigidly attached to a metal base 46 which, in turn, is preferably welded to an angle member 47 adapted to be attached to the supports 26 by removable screws, as above described.

As seen by reference to Fig. 1 of the drawings, the steel block 37 of the vibratory mechanism 30 is positioned to vibrate adjacent the ends of the magnet 41. As is well understood, vibratory motion of the block 37 will induce a potential in the coils 42 which, as is well known, will be proportional to the amplitude of vibration of said block 37. This amplitude of vibration of the block 37 is determined by and directly proportional to the amplitude of vibration of the deck 11 or the armature shaft 15 or any member which is rigidly attached to either of them. In other words, the voltage generated in the coils 42 will be proportional to the amplitude of vibration of the conveyor 10 or motor 28.

The coils 42 are connected over a pair of conductors in a cable 48 to an electrical control apparatus, at least a portion of which is housed in a cabinet 49 as seen in Fig. 1 of the drawings, which cabinet 49 may be supported on any desired means, such as a stand 50.

While I have illustrated one form of an electrical pick-up mechanism it is to be understood that any other form may be employed and in practice I have successfully used a piezo-electric crystal inertia type of electrical pick-up in place of that illustrated, which is directly connected to and supported by the deck 10, or a vibratory portion of the motor 28, the axis of vibration of which is carefully set at right angles to the plane of the crystal. It is to be understood that this type of pick-up may be substituted for that illustrated.

Referring particularly to Fig. 5 of the drawings, there is illustrated a circuit for the electrical control mechanism of my invention. The cable 48 is connected to the primary of a step-up transformer 51 which steps up the potential generated by the pick-up mechanism and feeds it to a high gain vacuum tube amplifier which may be of any desired form. In the drawings I have illustrated a two stage type of amplifier including a pentode tube 52 and a triode tube 75

53. The source of direct current potential for the amplifier is from a full-wave rectifier 54 of well known construction including a full-wave rectifier tube 55, the out-put of which is fed through a filter 56.

The circuits for the rectifier and amplifier may be traced as follows: current is derived from the usual source of alternating current of 110 volts by way of conductors 57 and 58 and line switch 59, of which conductor 58 has a control switch 60 in circuit therewith, leading to the primary of rectifier transformer 61. The two plates of the rectifier tube 55 are connected to opposite terminals of the secondary 61 of transformer 60, the center tap of which secondary 61 is grounded at 62. The filament of the tube 55 is heated by secondary 63 of the transformer 60. The positive terminal of the out-put circuit of the rectifier 55 leads to conductor 64 by way of the choke coil 65 which is a portion of said filter 56; said filter additionally including grounded condensers 66 one on each side of said choke coil 65, one of which is also preferably shunted by a multi-megohm resistor 67.

20 The transformer 60 also has another secondary 68 which heats the filaments of the tubes 52 and 53 and also lights a signal lamp 69 which will be illuminated whenever the switch 59 is closed, thereby indicating that power is supplied to the control circuit.

25 The potential generated in the secondary of transformer 51, as above described, is supplied to the in-put circuit of the tube 52 by virtue of the fact that one terminal of said secondary is connected to the control grid 70 of said tube 52 and the other terminal is grounded, the cathode 71 of said tube 52 being also grounded through resistor 72. The direct current plate or out-put circuit of said tube 52 is from plate or anode 73 thereof, conductor 74, multi-megohm resistors 75 and 76 to the positive conductor 64 of the aforescribed rectifier 54. As was above pointed out, the cathode of said tube 52 is connected to ground and the negative terminal of the rectifier 54 is also connected to ground 62, thus providing a plate or out-put direct current voltage between the cathode 71 and the anode or plate 73 of said tube 52.

30 It may additionally be mentioned that the pentode tube 52 is provided with a screen grid 77 which is connected to the positive conductor 64 through megohm resistor 78 and is connected to ground through condenser 79. In addition, said tube 52 is provided with suppresser grid 80 which is connected to the cathode 71 and to ground through condenser 79.

35 Connected across the resistor 76 is a decibel meter 80 provided with an adjustable shunting rheostat 81. It may be stated that the function of this decibel meter 80 is to give a direct measurement of the voltage generated by the pick-up mechanism and the reading of the scale thereof may be adjusted by the rheostat 81. In practice, when a desired amplitude of vibration of the deck or motor is realized rheostat 81 is adjusted to give any predetermined reading of the meter 80. Thereafter it is only necessary to adjust the amplitude of vibration of the conveyer or motor to give this same reading of the meter 80 to insure the same amplitude of vibration thereof.

40 The alternating current out-put circuit of the tube 52 extends from conductor 74 through condenser 82 and multi-megohm potentiometer rheostat 83 which is grounded to complete the

alternating current out-put circuit. The alternating current potential or an adjustable portion thereof across the potentiometer rheostat 83 is fed to the in-put circuit of the tube 53 of the amplifier over an obvious circuit including adjustable contact 84 associated with said rheostat 83 which leads to control grid 85. The cathode of said tube 53 is grounded through resistor 86 and condenser 87 in parallel. The direct current out-put circuit of the direct tube 53 is from plate or anode 88, multi-megohm resistors 89 and 90 by way of conductor 91 to the positive conductor 64 leading from the aforescribed rectifier 54.

Intermediate the resistors 89 and 90 is a condenser 92 leading to ground. It should have also been mentioned that the condenser 93 is also connected to ground between previously described resistors 75 and 76. The alternating current out-put circuit for the tube 53 leads from the conductor 91 through condenser 97 to one terminal of a full-wave bridge rectifier 98 which may be of the copper oxide type, the opposite terminal of which is grounded, thereby completing this alternating current circuit.

It is to be understood that the above-described rectifier, amplifier and filter are purely illustrative and any well known form of any of these mechanisms may be employed.

It is, of course, evident that the bridge rectifier 98 operates as a full-wave rectifier and converts the alternating current out-put of the amplifier into pulsating direct current which is fed over conductors 99 and 100 to the winding of a galvanometer type relay 101. The galvanometer type relay 101, in addition to the winding, includes a pointer 102 adapted to contact adjustable contacts 103 and 104 or to assume a position intermediate said contacts 103 and 104. The contacts 103 and 104 are carried on an adjustable mechanism and form a standard of comparison, that is, whenever a desired amount of current flows through the coil of the galvanometer 101 by way of conductors 99 and 100 the pointer 102 assumes a position between contacts 103 and 104 and out of contact with each of them. If the current becomes too low pointer 102 makes contact with contact 103 and if it becomes too high it makes contact with contact 104.

Both the contacts 103 and 104 are independently adjustable with respect to the carrier upon which they are mounted, thereby making it possible to adjust the allowed range of movement of the pointer 102 before either of said contacts was contacted thereby.

It is, of course, evident that the position of the pointer 102 will indicate the amplitude of vibration of the conveyer 10 or motor 28 and the range of movement thereof may be controlled by controlling the position of the contact 84 on potentiometer rheostat 83. Assuming that contact 84 has been adjusted so that pointer 102 assumes a desired position for a predetermined amplitude of vibration of the conveyer 10 or motor 28 the standard or carrier upon which contacts 103 and 104 are supported is adjusted so that pointer 102 is out of contact with each of said contacts 103 and 104. Said contacts 103 and 104 are then adjusted on the standard carrier so that a predetermined increase or decrease in the amplitude of vibration of the conveyer 10 or motor 28 will cause said pointer 102 to make contact with contact 104 or 103.

In other words, the amplitude of vibration of the deck is measured directly by the galvanometer 101 and this measurement is calibrated, and

upon a predetermined variation either above or below a predetermined value control means are set in operation which control means are now to be described.

5 A transformer 105 is connected to the source of alternating current supply by being connected across the conductor 57 and conductor 58' which is an extension of conductor 58 through switch 59 so that when said switch 59 is closed said transformer 105 is energized. Transformer 105 steps down the voltage on conductors 57 and 58' and feeds it to a full-wave bridge rectifier 106, preferably of the copper oxide type, the direct current out-put of which is fed to conductors 107 and 108 which have a high ohm resistor 109 connected between them, and switch 107' connected in series with conductor 107. Conductor 107 is connected to the pointer 102 of galvanometer relay 101. Conductor 108 is provided with a number of branches one of which leads to high or red signal lamp 110; another of which leads to low or green signal lamp 111 and others of which lead to the upper terminals of windings 112 and 113 of control relays 114 and 115 respectively. It is therefore evident that to energize any of said elements 110, 111, 112 and 113 it is only necessary to connect the other terminal of them to conductor 107.

15 It may be stated that the control relays 114, 115 are normally biased to the positions illustrated in Fig. 5 of the drawings in which positions said relays through upper contacts 116 and 117 close an obvious circuit to energize white or normal signal lamp 118 from the secondary 68 of transformer 60. Whenever the switch 59 is closed and the galvanometer type relay 101 is in its normal position, signal lamp 118 will be energized to indicate this fact. Should pointer 102 make contact with the contact member 103 this will effect a connection from conductor 107 by way of conductor 207 to energize low or green signal lamp 111 and the coil 112 of relay 114. Should pointer 102 make contact with the contact 104 this will effect a connection from conductor 107 by way of conductor 307 to energize high or red signal lamp 110 and the coil 113 of relay 115.

25 The relays 114 and 115 are operative to control a motor operated rheostat 120 which controls the amount of current flow to the field winding 24 of the motor 28 by controlling an impedance in series therewith.

30 It will be seen that the conductor 58' extends directly to one brush of the armature 121 of the motor operated rheostat 120, the other brush of which is connected by conductor 122 to the center of a reversing field winding 123 of a reversible type motor, including the armature 121 and winding 123, which is connected to drive an adjustable contact 124 of a rheostat or resistor 125 or other impedance adjusting mechanism. The opposite terminals of the winding 123 are connected over conductors 126 and 127 to movable contacts 128 and 129, respectively, of the control relays 114 and 115. Associated with said movable contacts 128 and 129 are cooperating stationary contacts forming complete switches, which stationary contacts are connected directly to the conductor 57.

35 It is thus evident that whenever winding 112 of relay 114 is energized contact 128 will move to circuit making position thereby to energize half of the winding 123 in series with the armature 121 and this in turn is effective to rotate the contact 124 to decrease the resistance or im-

pedance 125 which is in series with the field winding 24, which winding 24 is energized from main line conductors 130 and 131 through main control switch 132.

It may be stated that switches 57' and 132 should be opened simultaneously or closed simultaneously thus preventing any change of the rheostat 125 by the control system in case the amplitude of vibration of the vibratory conveyer motor is reduced to zero by de-energization.

To provide for adjustment of the rheostat 125 manually, I provide a reversible switch 133 leading from conductor 57 to be connected alternately to conductors 126 or 127 or to be in a neutral position. It is manifest that by virtue of switch 133 the motor operated rheostat may be manually adjusted either to increase or decrease the effective value of resistance 125 independent of the control system.

Energization of winding 113 of relay 115 will energize the other half of winding 123 in series with the armature 121 to increase the amount of the resistance or impedance in series with the field winding 24.

It is also to be noted that whenever relay 114 or relay 115 is energized the circuit to the white or normal light 118 is opened through one of the contacts 116, 117.

In the operation of the device comprising my invention, with the consequent realization of the method of my invention, the rheostat 125 is adjusted by control switch 133 to produce any desired amplitude of vibration of the vibratory conveyer 10 or motor 28 after switches 57' and 132 are closed. Switch 59 is then closed and after the amplifier and full-wave rectifier 54 have had time to come up to temperature the rheostat 81 is adjusted to give any desired reading of the decibel motor 80, preferably near the center of the scale thereof to act as a reference point. Contact 84 of the potentiometer rheostat 83 is then adjusted to bring the pointer 102 to any desired position and intermediate the contacts 103 and 104 carried by the standard of the galvanometer type relay 101 which is to determine the future control of the rheostat 125.

Under the conditions above specified the lamp 69 and the lamp 118 are energized, the former indicating that the full-wave rectifier and amplifier are in circuit and the latter indicating that the relays 114, 115 are in their normal de-energized condition. Switch 107' is then closed to make effective the control of relays 114, 115 by galvanometer relay 101. The apparatus is then under full automatic control.

Should the amplitude of vibration of the conveyer 10 or motor 28 decrease this will produce a decreased amplitude of vibration of the block 37 and a proportional decrease in potential of the transformer 51. This amplified potential is, of course, rectified and delivered to the galvanometer type relay 101 in which the current flow is thus reduced over the predetermined amount causing the pointer 102 to move from its predetermined value, as indicated by the standard, and make contact with the contact 103. This will cause an energization of the green signal lamp 111 and of the winding 112 of relay 114 which will close contact 128 and open contact 116, the former of which will cause the motor operated rheostat to operate and decrease the effective value of the resistance or impedance 125, the latter of which will break the signal circuit to the white or normal signal lamp 118.

It is to be particularly noted that until the

pointer 102 is returned to coincide with the standard of galvanometer relay 101 or, in other words, until the normal condition is realized, motor operated rheostat 120 will operate to reduce the impedance or resistance of rheostat 125. This insures that the amplitude of vibration will always be returned to this predetermined value.

If the amplitude of vibration increases above the predetermined value, as determined by the 10 relative positions of the pointer 102 and the standard of galvanometer relay 101, pointer 102 will make contact with the contact 104 to energize red signal lamp 110 and the winding 113 of relay 115 which, through contact 129, will operate the motor operated rheostat 120 to increase the resistance or impedance of rheostat 125 until the normal condition is again realized and will open the circuit to white lamp 118 through contact 117.

It is thus to be noted that not only does the system operate entirely automatically to measure the amplitude of vibration of the vibratory conveyer or motor, and to compare it with a standard predetermined indicator, and further, to adjust the current rate to maintain a uniform amplitude of vibration, but in addition, the condition of the system is indicated at all times by appropriate signals.

As was previously set forth, the resulting control system insures a constant feed rate of the feeder 10 in case the depth of the material on the deck is uniform; and in case the depth of the material is not uniform, such as when material is fed in batches, the system insures a continuous feeding of the material and the vibration of the deck or motor at a constant amplitude regardless of the amount of material which may be on the deck at any time.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In conveyer apparatus, the combination with a conveyer deck mounted for conveyer vibration, of an alternating current electro-magnetic motor connected to said deck to impart thereto vibrations equal in frequency to the frequency of the current applied to said electro-magnetic motor, an alternating current electrical circuit including an adjustable impedance for controlling the current flow thereto, means comprising an electric pilot motor for varying said impedance to effect variation of such amplitude of vibration, a pick-up mounted on said conveyer apparatus and adapted to generate potential in proportion to the amplitude of vibration, means comprising a galvanometer and an amplifier connected to said pick-up to indicate the amplitude of vibration, and means controlled by variations of the galvanometer reading above and below a predetermined setting to control said pilot motor and thereby vary said impedance to control the current flow to the electro-magnetic motor to strengthen the latter when the amplitude of vibration decreases and to weaken the said last-named motor when the amplitude of vibration increases, thereby regulating the amplitude of vibration to maintain the same constant under the control of the varying amplitudes themselves.

2. In an electrical system, the combination with a vibratory conveyer having a deck and a vibratory motor for vibrating said conveyer to convey material thereon, of an electrical circuit for said motor including an adjustable impedance for controlling the current flow thereto, an electrical pick-up adapted to generate a potential proportional to the amplitude of vibration of said deck, a galvanometer relay, amplifier and rectifier means between said electrical pick-up and said galvanometer relay for setting up a current flow to the galvanometer proportional to said voltage, and means controlled by said galvanometer relay for effecting variation of said impedance to regulate said amplitude of vibration.

3. In an electrical system, the combination with a vibratory conveyer having a deck and a vibratory motor connected to said deck to impart conveying vibrations thereto, of an electrical circuit for said motor including an adjustable impedance for controlling the current flow thereto, means adapted to generate a voltage proportional to any one of various amplitudes of vibration of said deck, a galvanometer, amplifier and rectifier means for setting up a current flow to said galvanometer proportional to said voltage to enable such galvanometer to indicate a predetermined amplitude of vibration of said deck, and means controlled by said galvanometer to vary said impedance to effect such regulation of the vibration of said deck that said predetermined amplitude may be maintained with varying loads on said deck.

4. In an electrical system, the combination with a vibratory conveyer having a vibratory conveyer deck and an electro-magnetic motor connected thereto to operate the same, of means mounted on said vibratory conveyer to generate a voltage proportional to the amplitude of vibration of said deck, an electrical circuit for said motor including a variable impedance to control the current flow to said motor, a galvanometer, means connected between said voltage generating means and said galvanometer for producing a current flow through the latter, a meter, means for adjusting said meter to indicate a predetermined amplitude of vibration, means for varying the current flow through said galvanometer to effect setting of the same in central position to indicate the aforesaid predetermined amplitude of vibration corresponding to a similar setting of said meter, and means responsive to

5 variation of current flow through said galvanometer due to variation from the aforesaid predetermined value of said amplitude of vibration to effect operation of said variable impedance to restore said amplitude of vibration to its predetermined value and to restore the reading of said meter and said galvanometer accordingly.

10 5. In vibratory apparatus, the combination with a vibratory electric motor having a vibrating member, an electrical circuit including an amplifier and means for measuring the amplitude of vibration of said vibrating member, means forming a standard of comparison with said amplitude measuring means having a predetermined normal relation therewith when the amplitude of vibration of said vibratory electric motor has a predetermined selected amplitude of vibration, and mechanism operable in response to variations in the amplitude of vibration of said vibrating member under the joint control of said measuring means and said standard to restore said amplitude of vibration to its predetermined selected value.

20 6. In vibratory apparatus, the combination with a vibratory electric motor having a vibrating member, an electrical circuit including pick up means responsive to the vibration of said vibrating member to generate a fluctuating voltage proportional to the amplitude of vibration of said member, amplifier and rectifier means for converting said voltage into a direct current voltage proportional thereto, and means responsive to variations of said direct current voltage to control the rate of current flow to said electric motor to maintain the amplitude of vibration of said vibrating member substantially at a predetermined selected value.

25 7. In vibratory apparatus, the combination with a vibratory electric motor having a vibrating member, an electrical circuit including pick up means responsive to the vibration of said vibrating member to generate a fluctuating voltage proportional to the amplitude of vibration of said member, rectifier means for converting said 30 voltage into a direct current voltage proportional thereto, and means responsive to variations of said direct current voltage to control the rate of current flow to said electric motor to maintain the amplitude of vibration of said vibrating member substantially at a predetermined selected value.

LEE P. DOYLE.
